J. E. VALENTINE

POWDER PUFF

Filed Sept. 27, 1919

Patented Aug. 21, 1923.

1,465,535

UNITED STATES PATENT OFFICE.

JOSEPH E. VALENTINE, OF FLUSHING, NEW YORK, ASSIGNEE TO VALMONT MANUFACTURING CO., INC., A CORPORATION OF NEW YORK.

POWDER PUFF.

Application filed September 27, 1919. Serial No. 226,881.

To all whom it may concern:

Be it known that I, JOSEPH E. VALENTINE, a citizen of the United States, residing at Flushing, in the county of Queens and State of New York, have invented a certain new and useful Powder Puff, of which the following is a specification.

My invention relates to powder puffs and has for its object to produce a machine-made powder puff which can be manufactured easily and economically from a minimum number of inexpensive parts, and which fulfills all desired requirements of use and compares favorably in appearance with the more expensive hand-sewn powder puffs.

A further object of my invention is to produce a powder puff thin enough to fit in the top of the small boxes of powder or rouge with which such powder puffs commonly are used.

A further object of my invention is to produce a powder puff the center of which is soft and flexible so that it can be used with caked powder or caked rouge called "compacts" which generally are made with a rounded top.

A further object of my invention is to produce a powder puff in which the handle is integral with the top material thereof and preferably fastened permanently in position by a simple, inexpensive, fastening device.

A further object of my invention is to produce a powder puff the top of which is plaited or is gathered to give the finished and attractive appearance of high grade, handmade and hand-sewn powder puffs.

Other and further objects of my invention will be apparent from the following description and from the accompanying drawings of illustrative embodiments thereof, in which drawings:

Figure 1 is a top perspective of a completed powder puff;

Figure 2 a top plan with the handle cut away just above the fastening device therefor;

Figure 3 a perspective of the two parts used in one embodiment to secure the upper and lower fabrics together and showing by means of dash lines another embodiment of the upper part;

Figure 4 a perspective of the two parts

in another embodiment used to secure the upper and lower fabrics together;

Figure 5 a central vertical section of one embodiment showing the upper and lower parts with the upper and lower fabrics in place just before they are pressed together to form the completed powder puff;

Figure 6 a central vertical section of one embodiment of a completed powder puff, and

Figure 7 a central vertical section of another embodiment of a completed powder puff.

Spaces in the drawings have been exaggerated in some instances in order to indicate clearly the construction.

Similar reference characters refer to similar parts throughout the drawings.

In the embodiments illustrated, the top part 1 of the puff is made of any desired fabric, preferably gathered at its central portion to form radial plaits and a central handle 2. The handle may be secured in position in any desired manner such, for example, as by a ring 3 which is bent or pressed in at one or more places to form a permanent and attractive securing device. A handle which cannot become detached and an attractive appearance for the top of the powder puff thus is obtained at the same time from a single piece of material at a low manufacturing cost.

In order to secure together upper fabric 1 and lower fabric 4 of the completed powder puff, I provide a thin, flat upper ring 5, and a shallow, cylindrical, lower ring 6 which preferably has its lower edge turned sufficiently to decrease the internal diameter of the ring at that point. The external diameter of upper ring 5 is less than the internal diameter of lower cylindrical ring 6 so that said upper ring will fit within said lower cylindrical ring and lock the fabrics therebetween when the rings are forced together in the manner described hereinafter.

The preferred method of producing the embodiments of the completed powder puff illustrated is to gather upper fabric 1 in plaits or in folds to form a top having an attractive appearance and a handle 2 in the center thereof, over which handle is slipped ring 3 which is secured in place by bending or pressing in its sides in any desired

number of places as shown, for example, in Figures 1 and 2. The part of upper fabric 1 below handle 2 is placed over upper ring 5 with the edges of the fabric inturned under the ring as indicated in Figure 5. Bottom fabric 4 is placed around cylindrical ring 6 with the edges of the fabric inturned over the top edge as indicated in Figure 5. The two fabric covered parts 5 and 6 then 10 are forced together and the upper and lower edges of lower cylindrical ring 6, or either edge, turned over upper ring 5, thereby clamping the fabric securely between said rings (which are concealed from view as indicated in Figure 6) and securing the desired thinness. The order of procedure may be changed as desired and is not intended to be fixed by a statement of order of procedure in the claims.

20 It will be seen that to form the completed powder puff including the handle, only five parts are necessary,—the two fabrics 1 and 4 and the three rings 3, 5, and 6. It requires no complicated assembling of parts and the 25 completed powder puff fulfills every requirement of use and appearance as satisfactorily as the most carefully and expensively made hand-sewn powder puff.

The embodiment illustrated in Figures 4 30 and 7 of the drawings is similar to the embodiment of Figures 3, 5, and 6. The principal difference is in upper ring 5 which has a slight flange 50 on its outer edge. This edge, however, is of less depth than the sides 35 of lower cylindrical ring 6 so that the edge or edges of said lower ring 6 may be turned over upper ring 5 to clamp the material properly in place and provide a thin edge for the completed powder puff.

40 As it is not essential in the embodiments illustrated that upper ring 5 be of any substantial width, a dash line has been added to said upper ring 5 in Figure 3 to indicate a narrow ring which may be flat or of any 45 desired shape in cross section. It is essential in this embodiment only that a frame or support for the upper fabric be provided, over which a lower part 6 is turned to hold upper and lower fabrics 1 and 4 securely in place.

Many modifications of my invention will 50 be apparent to those skilled in the art without departing therefrom or from the scope of the claims, my invention not being limited 55 to the particular embodiments chosen to illustrate it but consisting of upper and lower fabrics secured together to provide a thin powder puff with a soft center and an attractive top with a handle integral therewith. It is obvious, moreover, that plaits 60 may be formed in the upper fabric without the formation of a handle and over any form of supporting member whether ring-shaped or solid.

65 Throughout the specification and claims I

have used the term "ring" in the sense of an annulus or other member having supporting edges and a very narrow body portion as distinguished from a disk or similar member having a substantial body portion.⁷⁰

Having described my invention, what I claim and desire to secure by Letters Patent is:

1. A powder puff of the character described, including, in combination, a frame 75 formed of a pair of rings, one of said rings being less in exterior diameter than the interior diameter of the other so that it may be positioned therewithin, material covering the front face of one ring and other material covering the rear face of the other ring, the edges of both pieces of material being clamped between the exterior edge of the smaller ring and the larger ring, whereby said material is unsupported ⁸⁰ except at the edges of the frame so that both covers for substantially their full areas are flexible and yielding in use.

2. A powder puff, including, in combination, a frame, a cover for the front of ⁹⁰ said frame forming an impact portion, and a cover for the back of said frame, said covers being secured to the frame at their edge portions, said back cover having its central portion gathered together in the ⁹⁵ form of an upwardly projecting handle, and clamping means for holding said handle and the back cover in the formed shape.

3. A device of the character described, including, in combination, a frame formed ¹⁰⁰ of a pair of rings, one of said rings being less in exterior diameter than the interior diameter of the other so that it may be positioned therewithin, material covering the front face of one ring and other material ¹⁰⁵ covering the rear face of the other ring, the edges of both pieces of material being clamped between the exterior edge of the smaller ring and the larger ring, the central portion of said last mentioned material being gathered together to form an outwardly projecting handle and means for holding the handle in its formed shape.

4. A device of the character described, including, in combination, a frame formed ¹¹⁵ of a pair of rings, one of said rings having a vertical flange and an inwardly extending flange on its front face, the other ring being less in external diameter than the internal diameter of the first mentioned ring ¹²⁰ so that it may be positioned therewithin, a piece of material for covering the front face of said frame and another piece of material for covering the rear face of said frame, said pieces of material being of sufficient size so that their edges may be secured together between the exterior edge of the smaller ring and the vertical flange of the larger ring and said piece of material for the back having an intermediate ¹²⁵ ¹³⁰

part gathered together to form an upwardly extending handle portion which forms a plaited back cover, and securing means clamping said handle portion into its 5 formed shape and holding said back material in the form of a plurality of plaits. 5. As an article of manufacture, a powder puff including a cover for the front face thereof, a cover for the rear face thereof 10 having an intermediate portion gathered together to form an integral upwardly projecting handle, and means for holding the handle into its formed shape.

6. As an article of manufacture, a powder puff including a cover for the front face thereof, a cover for the rear face thereof having its central portion gathered together to form a handle integral therewith, the formation of said handle also forming plaits radiating therefrom, and means for 15 clamping the handle into its formed shape.

In testimony that I claim the foregoing, I have hereunto set my hand this 26th day of September, 1919.

JOSEPH E. VALENTINE.

Certificate of Correction.

It is hereby certified that in Letters Patent No. 1,465,535 granted August 21, 1923, upon the application of Joseph E. Valentine, of Flushing, New York, for an improvement in "Powder Puffs," an error appears in the printed specification requiring correction as follows: Page 2, line 97, claim 2, strike out the word "clamping"; and that the said Letters Patent should be read with this correction therein that the same may conform to the record of the case in the Patent Office.

Signed and sealed this 6th day of November, A. D., 1923.

[**SEAL.**]

KARL FENNING,
Acting Commissioner of Patents.
